UNITED STATES PATENT OFFICE.

CHARLES F. MEHL, HENRY B. LIEBLER, JABEZ NALL, AND EDWARD J. NOBBE, OF
CLEVELAND, OHIO.

SAFETY DEVICE FOR MOVING-PICTURE MACHINES.

1,395,724.

Specification of Letters Patent. Patented Nov. 1, 1921.

Application filed June 18, 1919. Serial No. 305,204.

To all whom it may concern:

Be it known that we, CHARLES F. MEHL, HENRY B. LIEBLER, JABEZ NALL, and EDWARD J. NOBBE, all citizens of the United States of America, residing at Cleveland, in the county of Cuyahoga and State of Ohio, have invented a certain new and useful Improvement in Safety Devices for Moving-Picture Machines; and we do hereby declare the following to be a full, clear, and exact description of the invention, such as will enable others skilled in the art to which it pertains to make and use the same.

This invention relates to new and useful improvements in safety devices, and particularly to a device for governing the current supplied to the electric light of a moving picture machine so that the current will be shut off from the projection light in case the film splits longitudinally or breaks transversely.

The object of this invention is to provide means for preventing the film from being set on fire by the projection light used to display the same and is an improvement on the device shown in our pending application.

Our invention therefore consists in the features of construction and combinations of parts, hereinafter described in the specification, pointed out in the claims and illustrated in the accompanying drawings.

In the accompanying drawing Figure 1 is a top plan of a device embodying our invention showing the rollers held up and out of contact with the film and with switch open. Fig. 2 is a side view of the same. Fig. 3 is a view corresponding to a central vertical section, showing a roller (in full lines) leaning against the film and also showing a roller (in dotted lines) in its lower position after the film has broken. Fig. 4 is a top plan corresponding to Fig. 3. Fig. 5 is a section on line 5—5, Fig. 3.

Again referring to the drawings, A represents a portion of a moving picture machine and B represents a strip of film. Our device comprises a box-like casing 5 preferably formed in a single casting and having an opening 6 at the front end and an opening 7 at the bottom. Toward the rear end of the casing 5 at each side is formed a bracket arm 8 by means of which the device may be mounted on the frame of a moving picture machine. Within the casing at the rear thereof is mounted a support 9 formed

of insulating material. On the upper surface of this support are arranged two standards 10 and 11 which are held in place by binding screws 12 and 13. On each standard is pivotally mounted a contact member 14 and 15. To the binding screws are secured the terminals of an electric circuit which controls switch operating mechanism for controlling the motor which drives the machine and the projection light (not shown). At the front end of the casing and extending transversely thereof is a small shaft 16. At the center of the shaft 16 is loosely mounted a lever 17, one arm of which is longer than the other, and the longer arm extends rearwardly and carries a contact member 18 which is adapted to engage the contact members 14 and 15 and close the circuit. The shorter arm of the lever 17 has a cam surface 17', the object of which will appear later. The lever 17 is insulated from the shaft 16 by suitable insulation 19. A pin 20 is mounted on the lever 17 at the rear of its point of support and extends transversely thereof. On the shaft 16 at each side of the lever 17 is loosely mounted an arm 21. The free end of each arm 21 is forked as shown at 22, and between the sides of the fork is mounted a small roller 24 on a pin 25. At the pivoted end of each arm 21 is formed an extension or finger 26 which is arranged to engage the pin 20 on the lever 17 when the arms swing down to their lower position. It will therefore be understood that when the roller carrying arms are inclined upwardly the fingers on the lower ends thereof will be out of contact with the lever 17 and the switch blade 18 on said lever 17 will engage the contact members, and the electric circuit will be intact, but if either of the arms falls to its lower position the finger on said arm will come in contact with the pin 20 on the lever 17 thereby tipping up the inner end of said lever and withdrawing the contact member 18 from the contact members 14 and 15.

The device is mounted on the moving picture machine in proximity to the film with the arms 21 inclined upwardly and the rollers resting against the strip of film. When the arms 21 are in this position the electric circuit will be complete and the machine will be running. Now, if the film breaks transversely or longitudinally one or both arms 21 will fall breaking the circuit as be-

fore described and extinguishing the projection light, and thereby preventing the broken ends of the film from igniting.

Now, as the arms 21 fall by their own gravity it is necessary to provide means for holding up the arms while the film is being arranged on or taken off the machine, and this means is arranged as follows:

On the outside of the casing at each side 10 near the front is pivotally mounted a link 27. A rod 28 is supported by said links and extends under the outer ends of the arms 21. A spring 29 is secured to one 15 end of the rod 28, and the other end is fastened to a pin 30 on the side of the casing. At one end of one of the links 27 is formed a handle 31. Now, when it is desired to hold the roller carrying arms 21 in their upper position, the handle 31 is 20 raised which swings up the rod 28 against the arms 21 and locks them in their upper position. As the rod 28 swings up it engages the cam surface 17' formed on the 25 forward end of the lever 17, causing the forward end to swing down. The inner end of the lever 17 will be raised up and will lift the switch blade 18 away from the contact points 10 and 11, thereby breaking the electric circuit. It is therefore impossible 30 to start the machine before throwing down the handle 31 which permits the rollers to fall against the film and at the same time frees the lever 17 which closes the electric circuit. The object of this arrangement 35 is to prevent the picture machine from being operated when the roller carrying arms are held up and away from the film.

What we claim is:—

1. The combination with a moving picture machine and the motor and light circuit therefor, of a switch, automatically operating means for opening the switch upon the breaking of the film, and means for simultaneously locking said automatically operating means in its inoperative position and said switch in its open position.

2. The combination with a moving picture machine and the motor and light circuit therefor, of a switch comprising a stationary member and a pivotally supported member arranged to swing toward and away from the stationary member, auto-

matically operating means for causing the pivotally supported switch member to swing away from the stationary switch member upon the breaking of the film, and means for simultaneously locking the automatically operating means in its inoperative position and the pivotally supported switch member in its open position.

3. The combination with a moving picture machine and the motor and light circuit therefor, of a casing, a switch member mounted in said casing, a switch lever pivoted in said casing and having a switch member to engage said first mentioned switch member, a pin extending transversely of said switch lever, an arm pivotally mounted at each side of the switch lever, rollers carried by said arms and adapted to rest against the film, each arm having a finger adapted to engage the pin on the switch lever and lift said lever when the arm falls to its lower position.

4. The combination with a moving picture machine and the motor and light circuit therefor, of a casing, a stationary switch member mounted at the rear of said casing, a switch lever pivoted in said casing and having a blade to engage said stationary switch member, a pin extending transversely of said switch lever, an arm pivotally mounted at each side of said switch lever, rollers carried by said arms and adapted to rest against the film, said arms having fingers adapted to engage the pin on the switch lever and lift said lever when the arms fall to their lower position, links secured on opposite sides of said casing, a rod carried by said links and extending under said arms, and a spring connected to said rod and said casing, the arrangement being such that when the rod is swung up it will lock the arms away from the film.

In testimony whereof, we sign the foregoing specification, in the presence of two witnesses.

CHARLES F. MEHL.
HENRY B. LIEBLER.
JABEZ NALL.
EDWARD J. NOBBE.
